(57) **CLAIM**

The ornamental design for a drinking mug handle, as shown and described.

DESCRIPTION

FIG. 1 is a perspective view of a drinking mug handle showing my new design;

FIG. 2 is a front elevational view thereof, the rear view being a mirror image;

FIG. 3 is an environmental top plan view thereof;

FIG. 4 is an environmental bottom plan view thereof;

FIG. 5 is a side elevational view thereof;

FIG. 6 is a top plan view thereof;

FIG. 7 is a bottom plan view thereof;

FIG. 8 is a perspective view of a 2nd embodiment of a drinking mug handle showing my new design;

FIG. 9 is a front elevational view thereof, the rear view being a mirror image;

FIG. 10 is an environmental top plan view thereof;

FIG. 11 is an environmental bottom plan view thereof;

FIG. 12 is a side elevational view thereof;

FIG. 13 is a top plan view thereof; and,

FIG. 14 is a bottom plan view thereof.

The broken line illustration of the mug in FIGS. 1-5 and 8-12 represent the environment in which the design resides and forms no part of the claim.
